UNITED STATES PATENT OFFICE.

GEORGE FERGUSON, OF QUINCY, MASSACHUSETTS, ASSIGNOR TO UNITED SHOE MACHINERY CORPORATION, OF PATERSON, NEW JERSEY, A CORPORATION OF NEW JERSEY.

METHOD OF MAKING TURN-SHOES.

1,381,910.

Specification of Letters Patent. Patented June 21, 1921.

Application filed June 7, 1920. Serial No. 387,040.

To all whom it may concern:

Be it known that I, GEORGE FERGUSON, a citizen of the United States, residing at Quincy, in the county of Norfolk and State 5 of Massachusetts, have invented certain Improvements in Methods of Making Turn-Shoes, of which the following description, in connection with the accompanying drawings, is a specification, like reference characters 10 on the drawings indicating like parts in the several figures.

This invention relates to the manufacture of turn shoes and is herein described in connection with the manufacture of a turn shoe 15 having a rubber sole.

It is customary in the manufacture of a turn shoe to place wrong side out upon the first last upper material such as a lined or unlined upper and a sole, to perform certain 20 operations upon the shoe while it is wrong side out, and then to complete the manufacture of the shoe by withdrawing the last, turning the shoe right side out, relasting it, and performing certain further operations 25 upon it. For convenience the manufacture will be considered as divided into two stages, the first comprising the steps which take place while the shoe is on the first last and the second comprising the steps which take 30 place while the shoe is on the second last. Referring then to the first stage more in detail, it is customarily practised commercially in the following manner. After having been assembled on the first last, the shoe 35 is presented to a pulling-over machine which tensions the upper material about the heel and toe portions and drives temporary tacks through it into the sole. The shoe is then presented to a lasting machine which tens- 40 sions the upper material all the way around the last or part way around, according to the type of shoe being made and, in either case, inserts temporary lasting tacks at intervals in the feather of the sole at the base 45 of the sewing rib or shoulder, after which the shoe is presented in succession to a sewing machine, a tack pulling machine and a seam trimming machine. In the method thus briefly described, the pulling-over and 50 lasting operations, including the insertion of the temporary tacks, are depended upon to tension the upper material about the last and sole, the subsequent sewing operation serving to fasten the upper material firmly

under the tension determined by the pulling-over and lasting operations. In the method there are thus two separate tensioning operations both of which involve the insertion of temporary tacks; and, after the completion of the sewing operation, these 55 tacks are removed and the seam trimmed. 60

Important general objects of the present invention are to substitute one tensioning operation which corresponds to the two hitherto performed, to obviate entirely the 65 use of tacks, and to tension the upper material prior to the sewing operation in such manner that in said operation the tension will be automatically increased. According to the present invention the upper material 70 is tensioned about the last and sole and its margin fastened, preferably by cement, to the top of the sewing rib or shoulder. By this procedure the upper material is caused to bridge the space between the outer edge 75 of the rib and the edge of the sole. The upper material is then attached to the sole, as by stitches, which pass through the bridging portion of the upper material and through the base of the rib so as to draw the 80 upper material down into the corner formed by the junction of the base of the rib with the feather of the sole. The extra tensioning effect thus produced on the upper material takes place automatically as the result 85 of the manner in which the shoe is lasted and requires no extra attention or manipulation on the part of the operator; and, in order to facilitate the sewing operation, the dimensions of the upper material are prefer- 90 ably made such that its edge extends only a short distance beyond the inner edge of the sewing rib. 95

Referring now to the accompanying drawings,—

Figure 1 is a cross-section in perspective of part of a turn shoe assembled upon the first last preparatory to being lasted, said shoe comprising an upper which has no lining;

Fig. 2 is a similar view of the shoe after it has been lasted;

Fig. 3 is a similar view of the shoe after it has been lasted and sewed, and

Fig. 4 is a view similar to Fig. 2 but showing a shoe in which the upper is lined.

Referring first to Figs. 1, 2 and 3, there is shown a turned shoe having a rubber sole,

the upper material comprising an unlined upper which is herein shown as a piece of fabric 5 and may be provided with the usual counter and box toe stiffeners (not shown).
5 The sole comprises a thread portion 7 and a sewing rib or shoulder 9, the sewing rib lying between a feather 11 and a gutter 13 which separates the rib from the raised middle portion of the sole. The purpose of
10 the rib is to provide means to facilitate the sewing of the upper material to the sole as well as means for attaching the lasted upper material to the sole prior to the sewing operation. With regard to this latter function, it should be noted that the rib 9 has a flat top which is comparatively broad, thus providing a considerable area of contact. The purpose of the raised middle portion 15 is to provide a filler; and the purpose of the
20 gutter 13 is to permit the needle of the sewing machine to pass through the rib without entering any other part of the sole. In order to facilitate the sewing operation, the dimensions of the upper material are such that when lasted over the sole it will not extend entirely across the gutter 13 but will leave a free passageway for the needle of the sewing machine.

In the manufacture of the shoe the upper material and sole are assembled wrong side out upon a last 17 and preferably placed in a lasting machine of the type shown in application Serial No. 220,242 filed in the name of Casgrain and owned by the same assignee as is the present application, although the lasting may be done by hand or by any suitable machine. Cement may be applied to the inside of the margin of the upper material at this time or previously as may be desired; 40 or a piece of material, such as friction fabric, adhesive on both sides, may be applied to the margin. Instead of rendering the inner margin of the upper material adhesive, the desired results may be obtained by coating the flat top of the rib 9 with cement or otherwise rendering it properly sticky. The lasting operation is now carried out, the upper material being tensioned about the last and sole and its margin pressed down upon the top of the rib 9. The shoe is now ready to be sewed.

Referring more particularly to Fig. 2, it will be noted that the lasted upper material bridges the space between the outer edge 21 of the sewing rib or shoulder and the adjacent edge 23 of the sole, and that the margin of the upper extends only part way across the gutter 13 and does not extend over or adhere to the raised middle portion 15 of the sole. The shoe is then sewed, preferably by a machine fitted with the usual curved needle 19. The needle passes through that portion of the upper material which bridges the space referred to above, the 65 stitches draw this portion down against the

base of the rib 9 (see Fig. 3), and this drawing action serves to put an additional tension on the upper to draw it about the last. After the manufacture of the shoe has reached this stage, the shoe may be completed in any of the usual ways which commonly comprise pulling the last, turning the shoe, inserting a shank stiffener, relasting the shoe and attaching the heel.

Referring now to Fig. 4, the same sort of sole is shown as in Figs. 1, 2 and 3. In this figure, however, the upper material comprises an upper proper 25, herein shown as made of leather, and a lining 27 which is made of fabric. The upper, it will be noted, is of such dimensions that when in lasted position its margin extends only part way across the top of the sewing rib or shoulder, while the lining extends beyond the edge of the upper so as to adhere to that portion of the top of the rib which is left exposed. The method of drawing the upper material 25, 27 about the last and causing its margin to adhere to the rib is the same as with the unlined shoe shown in Figs. 1, 2 and 3.

Although the method has been set forth in connection with the manufacture of a shoe having a rubber sole of a particular shape, it should be understood that the method may be practised with soles of other materials and forms.

Having thus described my invention, what I claim as new and desire to secure by Letters Patent of the United States is:

1. The method of making a turned shoe which comprises assembling wrong side out upon a last upper material and a sole provided with an upstanding rib spaced from the edge thereof, tensioning the upper material about the last and sole and fastening it to the top of the rib, sewing the upper to the rib by stitches which pass through the base of the rib so that, as the stitches are drawn tight, a further tension is imparted to the upper material, and subsequently turning the shoe right side out and completing its manufacture.

2. The method of making a turned shoe which comprises assembling wrong side out upon a last upper material and a sole provided with a sewing shoulder spaced from the edge thereof, drawing the upper material about the last, attaching it to the top of the sewing shoulder so as to bridge the space between the edge of the shoulder and the edge of the sole, attaching the upper material to the sole by fastening means which pass through the bridging portion of the upper material and draw it down into the corner at the base of shoulder, and subsequently turning the shoe right side out and completing its manufacture.

3. The method of making a turned shoe which comprises assembling wrong side out

upon a last upper material and a sole provided with a flat-topped sewing rib spaced from the edge thereof, cementing the margin of the upper material, drawing the upper 5 material about the last and sole and pressing its margin down upon the top of the rib to cause it to adhere to the top and to bridge the space between the edge of the sole and the adjacent edge of the rib, attaching the upper material to the sole by 10 stitches which pass through the bridging portion of the upper material and draw it down into the corner at the base of the outside of the rib and subsequently turning the 15 shoe right side out and completing its manufacture.

4. The method of making a turned shoe which comprises providing a sole having a flat-topped sewing rib spaced from the edge 20 thereof, a raised middle portion and a gutter separating the rib from the middle portion, and upper material of such dimensions that when lasted its margin will extend over the rib but not across the gutter, assembling the sole and upper wrong side out upon 25 a last, tensioning the upper about the last and sole and causing it to adhere to the top of the rib so that a portion of the upper bridges the space between the edge of the

rib and the edge of the sole, attaching the 30 upper to the sole by stitches which pass through the bridging portion of the upper and draw it down into the corner at the base of the rib and subsequently turning the shoe right side out and completing its manufacture. 35

5. The method of making a turned shoe which comprises assembling wrong side out upon a last a sole provided with a sewing rib spaced from the edge thereof and upper 40 material including an upper proper and a lining, the lining projecting beyond the edge of the upper, drawing the upper material about the last, causing the edge of the upper and an adjacent portion of the lining to adhere to the top of the rib and to bridge the space between the edge of the sole and the adjacent edge of the rib, attaching the upper material to the sole by stitches which pass through the bridging portion of the upper 45 material and draw it down into the corner at the base of the rib, and subsequently turning the sole right side out and completing its manufacture. 50

In testimony whereof I have signed my 55 name to this specification.

GEORGE FERGUSON
